CLAIM

The ornamental design for a desoldering tip replacement apparatus or the like, as shown and described.

DESCRIPTION

FIG. 1 is a front, top, and right-side perspective view of a desoldering tip replacement apparatus or the like showing our new design;

FIG. 2 is a front elevational view;

FIG. 3 is a rear elevational view;

FIG. 4 is a right side elevational view;

FIG. 5 is a left side elevational view;

FIG. 6 is a top, plan view; and,

FIG. 7 is a bottom plan view thereof.
